PINKING MACHINE

Victor J. Sigoda, Brooklyn, N. Y., assignor to Man-Sew Pinking Attachment Corp., New York, N. Y., a corporation of New York

Original application October 27, 1938, Serial No. 237,243. Divided and this application May 21, 1940, Serial No. 336,327

9 Claims. (Cl. 164—64)

This invention relates to pinking machines, the subject matter of the present application constituting a division of my pending application for patent filed October 27, 1938, Ser. No. 237,243.

5 My present improvements are applied more particularly to that type of pinking machine, in which the pinking wheel or cutter is operatively mounted above a suitable base plate adapted to be positioned over the opening of a sewing machine table or other support and suitably secured thereto. A pressure roller movably supported below the base plate cooperates with the pinker wheel, and a leaf or plate spring resiliently urges said roller upwardly to press the fabric materials 10 against the teeth of the pinker wheel.

The present invention has for its general object and purpose to provide a simple and easily operated means for regulating or adjusting the spring pressure on said roller.

20 More particularly, in a preferred embodiment of the invention, the pinker wheel shaft and its drive mechanism are mounted in a housing structure detachably secured upon the upper surface of the base plate. It is a further object of my invention to provide a spring pressure regulating means which is wholly mounted upon and supported by said housing structure so that the upper surface of the base plate will be clear or unobstructed by the adjusting screw or other manually operated part.

Another object of the invention is to locate the hand knob or manually operable element for actuating the adjusting means at a convenient 25 position on one side of the housing structure where it can be easily reached and operated by the worker.

With the above and other objects in view, the invention consists in the improved pinking machine and in the form, construction and relative arrangement of its several parts, as will herein-after be more fully described, illustrated in the accompanying drawing and subsequently incorporated in the subjoined claims.

40 In the drawing wherein I have illustrated one simple and practical embodiment of the invention and in which similar reference characters designate corresponding parts throughout the several views:

45 Fig. 1 is a vertical longitudinal section of a preferred embodiment of the machine, a fragment of the housing structure being shown in elevation.

50 Fig. 2 is a vertical transverse section taken substantially on the line 2—2 of Fig. 1, and

Fig. 3 is a bottom plan view.

Referring in detail to the drawing, 5 designates a base plate of suitable dimensions, having integrally cast therewith a continuous depending flange 6 defining a rectangular wall in plan, 5 which is adapted to be received in an opening of a sewing machine table or work bench (not shown). Any suitable means may be employed for the purpose of rigidly and detachably securing this base plate in position upon the table or 10 bench.

Upon the upper surface of the base plate 5, a housing structure 7 for the pinker drive mechanism is adapted to be detachably mounted by means of the screws or bolts 8. Since the specific form of the housing structure and the drive mechanism, constitute no essential part of the present invention, they will not be further described in detail. It will suffice to state that the 15 drive mechanism includes a shaft 9 to one end of which the pinker wheel 10 is suitably fixed. A fabric feeding disk 11 is associated with the pinking wheel at one side thereof and held in operative relation to said pinking wheel for automatic 20 self adjustment with respect thereto in accordance with the thickness of the fabric or the number of plies fed to the pinking wheel. As this automatic feed device is described and claimed in my copending application for patent above 25 identified, it will not be further described in detail.

The pinking wheel 10 and feed wheel 11 are located above an opening 12 in the base plate 5, and through this opening a roller 14 journaled in a cradle 15 pivotally mounted at one of its ends on the under side of the base plate as at 16, is projected upwardly into cooperative engagement with the pinking and feeding wheels by means of a stiff leaf spring 17. As clearly shown in Fig. 1 of the drawing, this spring is fulcrumed intermediate of its ends upon the bearing rod or pin 18 and has upward bearing contact at one end against a longitudinal end extension 15' of the cradle 15. As shown in Figs. 2 and 3 of the drawing this spring is located at one side of the vertical center line of the housing structure 7 and the other end thereof is disposed below a transversely elongated opening 19 in the base plate 5.

55 The adjusting means for regulating or varying the pressure of the spring 17 on the roller 14 includes a member 20 pivotally mounted within the housing structure 7, as at 21. Preferably this member is in the form of a bell crank lever hav-

ing an arcuately curved arm 22 extending transversely of the base plate 5 from the pivot 21 and downwardly through the opening 19 in the base plate, the lower end of said arm having transversely sliding contact upon the end of the spring 17 and exerting a downward bearing pressure thereon as clearly seen in Fig. 2 of the drawing. The other arm 23 of said lever extends vertically upward from the pivot 21 and to the upper end 10 thereof the inner end of the rod 24 is pivotally connected as at 25. This rod extends transversely of the housing 7, the other end portion thereof being threaded and projecting exteriorly of the housing through an opening in the side wall thereof. Upon this outer threaded end of the rod 24, the adjusting nut or hand knob 26 has threaded engagement and has contact against a suitable bearing surface 27 provided on the outer side of the housing wall.

20 It will be apparent from the above description that when the member 26 is rotated in the direction indicated by the arrow in Fig. 1, the rod 24 is drawn outwardly to rock the lever 20. The arm 22 of this lever is thereby moved downwardly through the opening 19, said lever arm in effect, constituting a cam exerting a downward pressure on the end of the spring 17 and moving transversely across its upper surface. The upward pressure of this spring at its other end to urge the roller 14 against the cutter wheel 10 and feed disk 11 is thereby increased. In this manner a very sensitive regulation or adjustment of the pressure action of roller 14, in accordance with the particular character of fabric material being operated upon can be obtained.

From the above description, it will be appreciated that I have provided an adjusting means for regulating the spring pressure on roller 14, which is not only simple and efficiently reliable in its operation but also of greatest convenience to the worker. By positioning the manually adjustable member 26 upon the side wall of the housing structure and in an elevated position above the base plate, it is easily accessible to the operator or worker. By removing this adjusting member from the base plate of the machine, the fabrics piled in front of the worker upon said machine base will not be injured or soiled and require removal before it is possible to manipulate said member and make the necessary adjustment.

It will further be noted that the adjusting means is easily accessible from the rear open end of the housing and may be readily removed when necessary by simply removing the pivot screw 21. Also as the adjusting means is carried by the housing structure, in assembling the latter upon the base plate 5 and securing the same by means of the bolts 8, the lever arm 22 is automatically positioned in proper bearing contact upon the end of the spring plate 17. Also by concealing the adjusting means largely within the housing, the general appearance of the machine is improved.

65 In the foregoing description and accompanying drawing, I have disclosed a practical embodiment of the invention which has given excellent results in practice. However, it is to be understood that my present improvements might 70 also be exemplified in numerous other alternative structural embodiments, as to form, construction and relative arrangement of the several elements. Accordingly, I reserve the privilege of incorporating the essential features in the present disclosure in such other equivalent embodi-

ments thereof as may be fairly comprehended within the spirit and scope of the appended claims.

I claim:

1. In a pinking machine, a base plate, pinking means and operating mechanism therefor, a housing for the latter, a pressure roller cooperating with the pinking means, means for applying variable pressure to said roller including a member fulcrumed on the base plate, a bell crank lever mounted in the housing and having one arm thereof in bearing contact with one end of said member, manually adjustable actuating means for said lever operatively connected with the other arm thereof, and means for detachably securing said housing on the base plate with said bell crank lever in cooperative relation to said pressure applying member. 5

10 2. In a pinking machine, a base plate, pinking means and operating mechanism therefor mounted upon the base plate, a pressure roller cooperating with the pinking means, an elongated resilient member fulcrumed intermediate of its ends below the base plate and having one end thereof disposed in pressure applying relation to said roller, the other end of said member being disposed below an opening in the base plate, a bell crank lever mounted above the base plate, one arm of said lever extending through said opening and having transversely movable bearing contact upon the latter end of said resilient member to tension the latter and variably regulate the pressure transmitted to said roller, and adjusting means for said lever connected to the other arm thereof. 15

20 3. In a pinking machine, a base plate, pinking means and operating mechanism therefor, a housing for the latter, a pressure roller cooperating with the pinking means, means for applying variable pressure to said roller including a member 25 fulcrumed on the base plate, a bell crank lever mounted in the housing and having one arm thereof in bearing contact with one end of said member, and a manually adjustable actuating means for said lever operatively connected to the other arm thereof. 30

35 4. In a pinking machine, a base plate, pinking means and operating mechanism therefor mounted upon the base plate, a pressure roller cooperating with the pinking means, an elongated resilient member fulcrumed intermediate of its ends below the base plate and having one end thereof disposed in pressure applying relation to said roller, a bell crank lever mounted above the base plate, one arm of said lever having transversely 40 movable bearing contact upon the other end of said resilient member to tension the latter and variably regulate the pressure transmitted to said roller, and adjusting means for said lever connected to the other arm thereof. 45

50 5. In a pinking machine, a base plate, pinking means and operating mechanism therefor mounted upon the base plate, a pressure roller cooperating with the pinking means, means for applying variable pressure to said roller including a member 55 fulcrumed on the base plate, a bell crank lever mounted above the base plate and having one of its arms in relatively movable bearing contact upon one end of said member, and adjusting means for said lever connected to the other arm thereof. 60

65 6. In a pinking machine, a base plate, pinking means and operating mechanism therefor, a housing for the latter, a pressure roller cooperating with the pinking means, means for applying var- 70

5
3
iable pressure to said roller including a member fulcrumed on the base plate, and adjusting means for said member carried by the housing and including a pivotally mounted lever having slideable bearing contact at one of its ends upon said member, and manually adjustable means mounted on a side wall of the housing and operatively connected with the other end of said lever.

7. In a pinking machine, a base plate, pinking means and operating mechanism therefor, a housing for the latter open at one end, a pressure roller cooperating with the pinking means, a member fulcrumed on the base plate having one of its ends positioned in pressure applying relation to said roller, a lever pivotally mounted within the open end of the housing for vertical movement transversely thereof having bearing contact at one of its ends upon the other end of said member, a manually adjustable element vertically spaced above the base plate at the outer side of the housing, and an operating connection between said element and the other end of said lever.

8. In a pinking machine, a base plate, pinking means and operating mechanism therefor, a housing for the latter, a pressure roller cooperating with the pinking means, means for applying var-

5
10
iable pressure to said roller including a member fulcrumed on the base plate with one of its ends in pressure applying relation to said roller, an adjusting element mounted within the housing in operative engagement with the other end of said member, and operating means for said element extending through a wall of said housing and comprising a manually adjustable member vertically spaced above the base plate at the outer side of the housing wall.

9. In a pinking machine, a base plate, a pinking means and operating mechanism therefor, a housing for the latter, a pressure roller cooperating with the pinking means, means for applying variable pressure to said roller including a member 15 fulcrumed on the base plate with one of its ends in pressure applying relation to said roller, an adjusting element pivotally mounted within the housing in operative engagement with the other end of said member, said element having a vertically disposed arm, a manually adjustable member vertically spaced above the base plate at the outer side of the housing, the means operatively connecting said member with said arm.
